STOPPING MECHANISM FOR PILE WIRE LOOMS.

No. 542,806.

Patented July 16, 1895.

UNITED STATES PATENT OFFICE.

GEORGE POOLE, OF LOWELL, ASSIGNOR TO THE MASSACHUSETTS MOHAIR PLUSH COMPANY, OF BOSTON, MASSACHUSETTS.

STOPPING MECHANISM FOR PILE-WIRE LOOMS.

SPECIFICATION forming part of Letters Patent No. 542,806, dated July 16, 1895.

Application filed July 27, 1894. Serial No. 518,691. (No model.)

To all whom it may concern:

Be it known that I, GEORGE POOLE, of Lowell, in the county of Middlesex and State of Massachusetts, have invented certain new and useful Improvements in Stopping Mechanism for Pile-Wire Looms, of which the following is a specification.

This invention has relation to pile-wire looms; and it has for its object the provision of means whereby the loom may be automatically stopped in case a wire breaks in the operation of withdrawing the same or in case the hook or other means fail to engage and withdraw a wire.

To these ends my invention consists in providing a feeler operated through the medium of devices connected with the lower or bottom shaft, so as that it may rest lightly against the wire when the latter is intact and while it is being withdrawn, and which feeler may move when not brought to a stop against the wire so as to operate latching or tripping devices connected with the shipper, and thus automatically "knock off" the loom.

Reference is to be had to the annexed drawings, and to the letters marked thereon, forming a part of this specification, the same letters designating the same parts or features, as the case may be, wherever they occur.

Of the drawings, Figure 1 is a side elevation of my improvements in the position they will occupy at the time that a wire is being withdrawn when the latter is intact. Fig. 2 is also a side elevation of my improvements, looking in the opposite direction from that in which the parts shown in Fig. 1 are viewed, the said parts being in the position they will occupy just after an intact wire has been withdrawn. Fig. 3 is a plan view of the wire box or magazine and immediately-connected parts with the feeler shown as resting against a wire which is in process of being withdrawn. Fig. 4 is a view similar to Fig. 1, but representing the position of the parts when a wire fails. Fig. 5 is a sectional front elevation of the parts shown in Fig. 2 and some additions thereto.

In the drawings, *a* designates the frame.

b is the lower or bottom shaft.

c is the wire box or magazine.

d is the wire bar, and *e* are the wires, each of which is provided with a head *f*.

The parts mentioned may be of usual or suitable construction and be employed in the ordinary manner.

g designates what I term a "feeler," which may consist of a lever fulcrumed, as at *h*, upon any suitable part of the frame and having its upper end *i* constructed and arranged when moved inward to bear or rest against the wire *e* when the latter is being withdrawn.

The lower portion of the feeler-lever *g* extends downward and is curved inward, and its lower inner end is pivotally connected with one end of a longitudinally-movable rod *h'* arranged in bearings formed in the bracket *i'*. The inner end of the said rod is bent at a right angle to the main or body portion, the angular part thereof extending back of a pendent lever *j*, provided toward its lower end with a notch or offset *k*.

l is a lever pivotally connected at its forward end to the lower end of a vertically-movable bar *m*, the upper end of which is adapted to act upon one arm of a detent or dog *n* on the shipping-rod *o*, with which intermediate means *p* are connected for the purpose of shipping the clutch-operating means *q* to automatically stop the machine.

The lever *l* is constructed and arranged to be engaged on its under side by a pin *r*, projecting from the side of a disk *s*, and to be raised thereby and lowered by its own gravity once at each rotation of the bottom shaft *b*, to which the said disk is secured.

So long as the rear end of the lever *l* is left free the said end will be raised and lowered by the action of the pin *r* thereon; but should pendent lever *j* be moved forward so as to cause the free end of the lever *l* to engage the notch or offset *k* the said inner end of the said lever *l* will be held against rising and the forward end will be raised, raising the bar *m*, and through it knocking off and stopping the loom.

t is a lever pivoted at its rear end to a stationary part of the loom and provided at a point intermediate of its ends with a bowl or roller *u*, which rests upon a disk *v* on the bottom shaft *b*. The lever *t* is curved upward at

its forward end and is adapted at this point, when raised, to act upon a pin *w* projecting laterally from the lower arm of the feeler *g*. The disk *v* is provided with a depression *x* and 5 a raised surface *y*, as shown. The disk *v*, with its depression *x* and raised surface *y*, is in effect a cam.

The disks *s* and *v*, I may term for the sake of convenience a "movable" or "rotary" member, since they are both mounted on the bottom shaft and turn together as one piece, having on one side a cam-surface and on the other side a pin.

The operation of the invention is as follows: 15 At all times than just while the wire is being withdrawn the bowl or roller *u* will be on the raised portion *y* of the disk, which will have the effect of raising the free end of the lever *t* into contact with the pin *w* on the lower arm 20 of the feeler *g*, raising said lower arm and throwing the upper end or feeler proper *i* back and moving the rod *h'* rearward, so as not to affect the normal position of the pendent lever *j*. While an intact wire is being withdrawn 25 the bowl or roller *u* will run in the depressed part of the disk *v*; but the feeler *g* will still remain in position, as before, by reason of the fact that the upper end *i* will be held back by contact with the wire. Should, however, a 30 wire fail to be withdrawn or should it break, the upper end *i* of the feeler *g* will move inward, the lower arm will gravitate outward or forward, drawing the rod *h'* and pendent lever *j* in the same direction and causing the inner 35 end of the lever *l* to engage the notch or offset in the said pendent lever, so that the forward end thereof and the bar *m* will be raised, with the effect of knocking off and stopping the loom, as before described. By this means 40 a thoroughly efficient and certain device is provided for stopping the loom in the case of failure or breakage of a wire, and all of the mischief attendant upon such failure or breakage is avoided.

45 Having thus explained the nature of the invention and described a way of constructing and using the same, though without attempting to set forth all of the forms in which it may be made or all of the modes of its use, it 50 is declared that what is claimed is—

1. In a pile-wire loom, in combination, a shaft (*b*) provided with a cam and a disk having a pin, a knock-off mechanism, a feeler-lever adapted at one end to rest against the 55 wire when the latter is intact and being withdrawn, a pendent lever (*j*), a rod (*h'*) connecting the lever (*j*) with the other end of said

feeler-lever, a movable bar (*m*) connected to said knock-off mechanism, a lever (*l*) connected to said bar (*m*) at one end, a lever (*t*) pivoted at one end and provided with a roller to engage said cam, the free end of the lever (*t*) being arranged to engage said feeler-lever and the free end of the lever (*l*) being arranged to be engaged by the lever (*j*) substantially as 60 and for the purpose set forth.

2. In a pile-wire loom in combination, a cam carried by a disk *v*, a feeler lever adapted at one end to bear against the wire, while the latter is intact and being withdrawn, and means 70 actuated by said cam for operating said feeler lever to hold its above mentioned end out of the path of the said wire, while the latter is being inserted, substantially as and for the purpose set forth.

75 3. In a pile-wire loom in combination, a pin carried by a disk *s*, a feeler lever adapted at one end to bear against the wire, while the latter is intact and being withdrawn, a knock-off mechanism, a lever *k* connected to said feeler 80 lever, a lever *l* connected at one end to said knock-off mechanism, and adapted at its free end to be engaged and held by the lever *k* when the latter is operated by the feeler lever on the failing of a wire, said pin being arranged to engage the lever *l* between its ends, 85 whereby upon the breaking or failing of a wire, the knock-off mechanism will be operated, and whereby at other times the movements of the lever *l* will not affect the knock-off 90 mechanism, substantially as and for the purpose set forth.

4. In a pile-wire loom in combination a feeler lever pivoted to a stationary support, and adapted at one end to bear against the 95 wire, while the latter is intact and being withdrawn, a knock-off mechanism, a rotary member carried by the bottom shaft, and interlocking connections between the feeler lever and said rotary member, and between said rotary 100 member and said knock-off mechanism, adapted to be operated by said feeler lever, whereby upon the failing of a wire, said knock-off mechanism will be operated to stop the loom through the medium of the rotary member, 105 substantially as and for the purpose set forth.

In testimony whereof I have signed my name to this specification, in the presence of two subscribing witnesses, this 2d day of July, A. D. 1894.

GEORGE POOLE.
